SNAP FASTENER DISPLAY CARD

Romaine C. Chapman, West Cheshire, and William W. Borowy, Oakville, Conn., assignors to Scovill Manufacturing Company, Waterbury, Conn., a corporation of Connecticut

Application June 1, 1951, Serial No. 229,484

5 Claims. (Cl. 206—80)

1

This invention relates to a counter display card and package for snap fastener elements of the type that can be attached easily to garments in the home.

In supplying snap fasteners for attachment to garments in the home, it is necessary to provide in addition to the socket the stud elements themselves, means for attaching each of those parts. This can be in the form of a prong ring and for more detailed description of one common type of such snap fasteners, reference may be had to Fenton Patent No. 2,131,347. It is desirable in many instances to combine with one of the prong rings a decorative cover cap such as mother of pearl, simulated pearl or other types of ornaments.

A display card for this combination of elements presents some difficulty in that the prong rings have sharp points which must be protected and cannot be attached directly to the card, and when decorative covers are used with the prong rings it is desirable to have the ornamental side always exposed to view on the card. The socket and stud elements themselves can be snapped together in holes in the card.

According to our invention an inverted cup-shaped transparent member is placed against the card to provide a storage compartment and is detachably held to the card by the socket and stud elements snapped through holes in the cards and cooperating with the rim of the transparent member with the prong rings confined in the compartment between such member and card. The distance between the raised portion of the cup-shaped member and card is substantially the same as the overall height of the prong ring which carries the decorative cover so that those members cannot be disturbed from the original position and always present the ornamental side to view.

Referring now to the accompanying drawing illustrating a preferred embodiment of the invention, wherein

Fig. 1 is a plan view of the support card with the snap fastener elements and a transparent compartment member attached thereto.

Fig. 2 is a side view of the same.

Fig. 3 is a fragmentary cross sectional view taken along the line 3—3 on Fig. 1 and on an enlarged scale.

Fig. 4 is a plan view of the transparent compartment member, per se.

Fig. 5 is a side view of the same.

Fig. 6 is a plan view of the support card, per se, showing the arrangement of the openings for receiving the complementary snap fastener elements, and

2

Fig. 7 is a perspective view of one of the attaching members having an ornamental cap.

In the drawing the support is shown as a rectangular piece of cardboard 10 or some similar relatively stiff material having a series of holes 11 preferably arranged symmetrically in the order of a square and pierced therethrough.

To provide a compartment on the face of the card 10, a transparent cover or cup-shaped member 12 is provided that consists of a central cupped section 13 having a radially extending flange or rim 14 adapted to lie against the face of the card 10 and provides therewith a hollow compartment 15. Extending outwardly from the rim 14 is a series of lugs 16 equally spaced thereabout and with central pierced openings 17 that are positioned to line up with the openings 11 in the card 10.

Each set of complementary fastener elements 20 attached to the card 10 consists of a socket element 18 having spring fingers 19 and a stud element 20 having a projecting head or a stud 21, both elements having like circumferentially arranged anvil portions 22 and 23, respectively.

The stud elements 20 are arranged on one side of the card 10 with the stud head projecting through the card opening 11 and the flange lug opening 17 while the socket elements 18 are arranged on the opposite side of the card 10 positioned against the lug 16 and with their spring fingers 19 disposed inwardly toward the face of the card 10 and engaging the stud heads 21 projecting therethrough for detachably holding the compartment member 12 against the face of the card 10. For attaching either part of the snap fastener to a garment there is provided the usual form of prong ring 24.

This display card 10 is intended primarily to market a special ornamental type of snap fastener to be used where a part of the fastener is to be exposed on a garment such as on dresses, sport shirts, nurses' uniforms or as a cuff link. To this end one of the pronged rings 24a is adorned with an ornamental cap 25 such as synthetic pearl or glass crystal held upon the pronged ring by a retaining ferrule 26 (see Fig. 7).

In making up a display card there will be placed both the regular attaching ring 24 as well as the special ornamental ones 24a into the compartment 15. The fact that the compartment member 12 is made of transparent material will clearly show the character of the attaching ring ornamentation so that a choice can be made from the counter display for matching the fastener to a particular type of colored garment.

To show the ornamental pronged rings 24a to

best advantage the rings 24a are assembled into the compartment 15 with the pointed ends of the prongs resting against the face of the card 10 and the ornamental cap 25 uppermost so as to be seen through the transparent cap 12. To hold the pronged rings 24a in the above position the height of the base of the cupped section 13 of the cap 12 above the face of the card 10 is substantially the same as the decorative prong ring so as to prevent the ornamental pronged rings 24a from loosely juggling or tumbling around in the compartment 15 such as might cause them to tilt upon their sides or become inverted in the normal handling of the display card.

As a modification of the patent drawing disclosure, it is conceivable that the lugs 16 and openings 17 could be omitted from the rim 14 of the compartment 12 and to rely on the rim 14 itself engaged underneath the adjacent portions of the stud and socket members attached to the card 10 and detachably hold said member 12 against the face of said card. This form of invention would eliminate the need of having to align a number of openings in making the assembly.

While the form of invention herein shown and described embraces a preferred embodiment of the same, it is to be understood that the construction may be varied without departing from the spirit of the invention and the scope of what is claimed.

We claim:

1. A display package for complemental snap fastener elements having common attaching members and comprising a card having a series of complemental snap fastener elements detachably secured to the card, a transparent hollow member providing with the face of the card a closed compartment for storing the attaching members to be used in assembling the fastener elements to a garment, and means on said transparent member cooperating with said snap fastener elements to maintain said transparent member in detachable engagement with said card.

2. A display package for complemental snap fastener elements having common attaching members and comprising a card having a series of complemental snap fastener elements detachably secured to the card, a transparent cup-shaped member having a radially extending rim flange disposed against the face of said card, said cup-shaped member and adjacent face of said card providing a closed compartment for storing the common attaching members to be used in assembling the fastener elements to a garment, and said rim flange cooperating with said snap fastener elements attached to said card for detachably holding said cup-shaped member secured to said card.

3. A display package for complemental snap fastener elements having common attaching members and comprising a card having a series

of openings, a transparent cup-shaped member having a radially extending rim flange disposed against the face of said card, said rim flange having a series of openings arranged to align with said card openings, complemental snap fastener elements having detachable engagement through the aligned openings in said card and rim flange to hold said cup-shaped member against the face of said card and which provides therewith a closed compartment, said compartment serving to store said snap fastener attaching members in visible display upon the card.

4. A display package for complemental snap fasteners including stud and socket parts and prong ring attaching members at least some of which have ornamental cover caps, a card having a series of holes, a transparent cup-shaped member disposed in inverted position on the face of said card, said member having a flat rim with holes to match the holes in the card and a flat raised central portion spaced from the card substantially the same as the overall height of the ornamented prong rings to confine them in position to expose the ornamented side to view, and said cup-shaped member being detachably held on the card by the stud and socket parts snapped together through said matching holes.

5. A display package for complemental snap fasteners including stud and socket parts and having common attaching members some of which are provided with ornamental caps, said package comprising a card having a series of complemental fastener elements detachably secured to the card, a transparent cup-shaped member having a radially extending rim flange disposed against the face of the card, said cup-shaped member and adjacent face of the said card providing a closed compartment for storing the attaching members to be used in assembling the fastener elements to a garment, and said rim flange being held between the stud and socket parts which are snapped together through holes in the card, the height of the base of said cup-shaped member above the face of the card being such as to prevent the ornamental attaching member from loosely tumbling around in said compartment.
